UNITED STATES PATENT OFFICE.

LEOPOLD J. COURTEAU, OF BROCKTON, MASSACHUSETTS, ASSIGNOR TO UNITED SHOE MACHINERY COMPANY, OF PATERSON, NEW JERSEY, A CORPORATION OF NEW JERSEY.

MACHINE FOR SUPPORTING SHOE-UPPERS.

No. 891,912.

Specification of Letters Patent.

Patented June 30, 1908.

Application filed June 7, 1906. Serial No. 320,611.

To all whom it may concern:

Be it known that I, LEOPOLD J. COURTEAU, a citizen of the United States, residing at Brockton, in the county of Plymouth and 5 Commonwealth of Massachusetts, have invented certain Improvements in Machines for Supporting Shoe-Uppers, of which the following description, in connection with the accompanying drawings, is a specification, 10 like reference characters on the drawings indicating like parts in the several figures.

This invention relates to machines for supporting parts of shoes while they are fitted and secured together, and in particular to 15 machines which support and hold the lining in proper position while the upper is cemented thereto preparatory to stitching these parts together.

The objects of the invention are to facilitate 20 the cementing operation, to prevent wrinkling, and to secure accuracy in positioning the parts with respect to each other. These objects are accomplished by providing a form-block upon which one of the parts, the 25 lining for instance, is supported and held smoothly in position while another part, the upper for instance, is cemented thereto. The form-block has the shape which it is desired the cemented parts shall assume in the finished shoe, and means are provided for holding 30 one of the parts in smooth condition, so that cement may be applied expeditiously to the desired portions, and the other part fitted accurately thereon. If desired the form-block 35 may be rotatably mounted to permit it to be rocked in order that the operator may fit the work more expeditiously.

Referring to the drawings,—Figure 1 is a side elevation of the machine; Fig. 2 is a top 40 plan view; Fig. 3 is a view partly in end elevation and partly in section, and Fig. 4 is a detail perspective view.

Referring to the drawings, 1 designates a base of suitable construction having standards 2 provided with journaled bearings 3. Rotatably mounted in these journaled bearings is a form-block 4 having a shaper 5 which forms its upper portion and which has the contour which it is desired to give to the 50 back portion of the shoe upper and the lining thereof. This shaper is preferably detachably connected to the block in any suitable manner. That shown in the drawings is by means of a dovetail connection 7 and removable 55 screws 8 which are adapted to engage in

seats provided therefor in the shaper to prevent its accidental displacement. In a recess 9 in the block is slidably arranged a head 10 having an annular recess 11. Connected to opposite sides of the block are bearings 12 60 in which are pivotally arranged elbow levers 14 carrying a plurality of clamping arms 13 on their outer flattened ends. These clamping arms are preferably made of thin steel and engage the lining at a plurality of places. 65 The inner ends of said levers engage in the recess 11 of the sliding head, which is provided with a stem 15 passing out through one of the hollow journal bearings 3. A suitably mounted elbow lever 16 is arranged with one 70 end in operative engagement with said stem and its other end is connected to a treadle 18 by means of a link 17. This link is provided with a return spring 19. In the recess in which the sliding head moves is a spring 20 75 which bears against the head at one end and against an abutment 21 at its other end.

The parts are so arranged that normally the clamping arms are held against the sides of the block by the force exerted by the 80 spring 20. Upon depressing the treadle 18, the sliding head 10 is moved against the tension of the spring 20 and by means of the levers 14 causes the clamping arms to move away from the block. When the treadle is 85 released the spring 20 causes the arms to assume their normal position against the sides of the block. This operation is illustrated in Fig. 2 in which the normal position of the arms is shown in full lines and the 90 open position in dotted lines. Means are provided for rocking the block 4 to enable the operator to fit the work upon the block and smooth it out without moving about the machine or craning his neck for that purpose. This is accomplished by means of the drum 22, shown in detail in Fig. 4, which is mounted or formed on a hub 23 extending from the block and to which a belt 24 is secured at 25. This belt is thus secured near 100 its middle and passes off the pulley in opposite directions, its ends being connected with the treadles 26 and 27.

It is designed, according to this invention, 105 that the shaper 5 shall constitute the upper part of the form-block and that the lining shall be folded over this shaper with its middle rear part resting upon the top and the sides resting against the sides of the block; and that the operator shall, with his 110

hands, smooth out the lining over the shaper and along the sides of the block. By actuating the treadle the operator causes the clamping arms to open to permit the fitting and 5 smoothing out operation to be accomplished after which the treadle is released and the arms automatically engage the lining and hold it in the smoothed-out condition which has been imparted thereto by the operator 10 and maintain it in this condition until the shoe upper has been fitted thereover and the two secured together. While the lining is held by the clamping arms it is provided along the usual lines or parts with cement. 15 The operator will then place the upper over the lining and smooth it out as was done with the lining, and the upper will become attached to the lining on the portions to which cement is applied. When this has been 20 done the operator will depress the treadle 18 and the clamping arms will move away from the sides of the block, thus releasing the lining, and the latter together with the upper will be removed by the operator. As stated, 25 the block 4 is capable of being rocked in the journal bearings in order that the operator may, without moving around the machine, observe the work while it is progressing, and thus the operation of smoothing out the 30 lining and the upper may be facilitated. This rocking operation may be accomplished, as previously described, by manipulation of treadles 26 and 27.

While in the above description a complete machine has been set forth in detail, it will be understood that various changes may be made in construction and in details without departing from the spirit of this invention. 35

Having described my invention, what I 40 claim as new and desire to secure by Letters Patent of the United States is:—

1. In a machine of the class described, the combination with a form-block upon which part of a shoe is supported, of means to hold 45 said part in position on said form-block, means for rocking said form-block, and means under the control of the operator for shifting the holding means with respect to the form-block.

2. In a machine of the class described, the combination with a form-block, of means for rocking said form-block, a shaper detachably connected thereto upon which part 50 of a shoe is shaped, means to hold said part when shaped, and means under the control of the operator for shifting the holding means with respect to the form-block.

3. In a machine of the class described, the combination with a form-block upon which 55 part of a shoe is supported and means for rocking said form-block, of clamping arms arranged to bear upon said form-block, and

yielding means to hold said arms upon said form-block.

4. In a machine of the class described, the 65 combination with a form-block upon which part of a shoe is supported and means for rocking said form-block, of clamping arms to hold said part in position on said form-block, and a single spring to hold said arms 70 yieldingly upon said form-block.

5. In a machine of the class described, the combination with a rotatably mounted form-block upon which part of a shoe is supported as the shoe is assembled, of means to hold 75 said part in position on said form-block, and means under the control of the operator for rocking the form-block.

6. In a machine of the class described, the combination with a form-block upon which 80 part of a shoe is supported and means for rocking the form-block, of means arranged to bear normally upon the form-block to hold said part in position on said form-block, and means under the control of the operator 85 for moving the holding means away from the form-block.

7. In a machine of the class described, the combination with a rotatably mounted form-block upon which part of a shoe is supported 90 as the shoe is assembled, of means to hold said part in position on said form-block, means under the control of the operator for shifting the holding means relatively to the form-block, and means under the control of 95 the operator for rocking the form-block.

8. In a machine of the class described, the combination with a form-block upon which part of a shoe is supported, of a head slidably mounted in a recess in the form-block, a lever 100 pivotally secured to the form-block, one arm of the lever being engaged by said head, clamping arms secured to the other arm of the lever, a spring in said recess arranged to move said head in one direction, and a 105 treadle arranged to move said head in the opposite direction against the tension of the spring.

9. In a machine of the class described, the combination with a rotatably mounted form-block upon which part of a shoe is supported, of clamping arms to hold said part in position, a drum on said form-block, a belt secured near its middle to said drum, and a pair of treadles to which the ends of said 110 belt are secured for rocking said form-block.

In testimony whereof I have signed my name to this specification in the presence of two subscribing witnesses.

LEOPOLD J. COURTEAU.
